United States Patent Office

Des. 190,303
Patented May 9, 1961

190,303

BOTTLE CAP OR SIMILAR ARTICLE

Earl L. Conklin, Fort Lee, N.J., assignor, by direct and mesne assignments, to Century Brewery Corporation,
New York, N.Y., a corporation of New York

Filed May 21, 1959, Ser. No. 56,018

Term of patent 14 years

(Cl. D58—26)

Fig. 1

Fig. 2

Fig. 3

Fig. 5

Fig. 4

Fig. 1 is a front elevational view of a bottle cap or similar article, showing my new design;

Fig. 2 is a side elevational view thereof;

Fig. 3 is a top plan view thereof;

Fig. 4 is a bottom plan view thereof; and

Fig. 5 is a cross-sectional view on a slightly enlarged scale taken on line 5—5 of Fig. 3.

I claim:

The ornamental design for a bottle cap or similar article as shown.
